CONNECTING ROD ALIGNING AND
SUPPORTING FIXTURE

Wallace F. Mitchell, Chicago, Ill., assignor to
Ammco Tools, Inc., North Chicago, Ill., a corporation of Illinois

Application September 8, 1947, Serial No. 772,649

5 Claims. (Cl. 51—98)

1

This invention relates generally to a work-supporting fixture for a honing machine, and it has to do particularly with a fixture adapted to support and align a connecting rod in honing position on a honing machine of the character, for example, disclosed and claimed in my pending patent application Serial No. 632,908, filed December 5, 1945, which matured as Patent No. 2,483,590, dated October 4, 1949 for Bench type honing machine.

One of the objects of my invention is to provide a fixture which will support a connecting rod so that its piston pin bearing may be honed and simultaneously may be aligned accurately with its crank shaft bearing as an incident to the honing operation.

Another object is to provide a fixture of the foregoing character which eliminates bell-mouthing of the piston pin bearing during the honing operation, thereby insuring true honing of the bearing even though it is done by a careless or unskilled workman.

A further object is to provide a fixture of the foregoing character which is self-adjusting to accommodate connecting rods of various lengths which may be encountered in the ordinary servicing operations.

Still another object of the invention is to reduce the cost of servicing connecting rod bearings by reducing the time required for the servicing operation and by obtaining the desired results without the necessity of using highly skilled workmen.

Additional objects are to provide a connecting rod support for a honing machine by which the combined honing and connecting rod aligning operations are materially speeded up; to eliminate the necessity of aligning operations subsequent to the honing operation; and to provide means whereby the aligning and honing of connecting rod bearings may be carried out with greatly increased efficiency at a lower cost.

The invention comprises other and further features hereinafter set forth and more particularly defined in the appended claims and illustrated in the drawings wherein—

Figure 1 is a front elevational view of one form of fixture embodying the invention mounted on a honing machine and illustrating a connecting rod in broken line supported on the fixture in the honing position;

Fig. 2 is a side elevational view of the structure of Fig. 1 with a portion of the honing machine omitted; and

Fig. 3 is a sectional view of the fixture shown

2

in the previous figures and as viewed on lines 3—3 of Fig. 2.

A fixture embodying my invention is adapted for use with any suitable honing machine; however, it is particularly well adapted for use with a honing machine 10 of the type disclosed in my aforesaid pending application Serial No. 632,908. To mount the fixture of my invention on the honing machine 10, I provide an accurately machined surface 11 at the front of the honing machine casing, which surface is disposed at an angle of 90° with respect to the horizontal and vertical axial planes of the hone tool 12. The hone 12 projects outwardly from the front of the machine 10 where it is readily accessible to the operators, and, while any suitable hone may be used, I prefer the hone shown and described in my pending application, Serial No. 615,165, filed September 8, 1945, which matured as Patent No. 2,445,277, dated July 13, 1948.

A preferred form of my invention is illustrated in Fig. 1. The structure there shown comprises a rectangular bar 13, the right end of which is removably and rigidly secured to the surface 11 of the machine 10 by bolts 13a or other suitable fastening means, so that the body of bar 13 is disposed in a plane parallel to the surface 11. The bar 13 projects laterally and its free end is provided with an opening 14 adapted to receive the reduced threaded end of a rod 15. The rod 15 is fixed to the bar 13 by a nut 16 and it extends perpendicularly and forwardly from the bar 13 in parallel relation to the axis of the hone 12. The rod 15, which is of circular cross-section and of uniform diameter throughout its length, has a smooth surface finish to minimize frictional resistance therewith. The rod 15 slidably and rotatably supports a work supporting member 17 which will now be described.

Specifically the member 17 comprises a body 20 having bearing elements 18 and 19 at each end thereof. The body 20 intermediate the bearings 18 and 19 is cut away to give it a semi-circular cross-sectional shape, which portion has an internal diameter greater than the outside diameter of the rod 15 to provide a clearance 21 with the rod. In this manner, the frictional contact between the rod and the work-supporting member is restricted to the bearing elements 18 and 19 and the weight of the structure is reduced. Each of the bearing elements 18, 19 is provided with means, such as bolts 22, for adjusting and clamping such bearings for a fixed radial clearance with the rod which preferably is only an amount sufficient to permit the member

17 to be moved freely both axially and circumferentially on the rod 15. The purpose of the slideable and rotatable movement of the member 17 will be described presently.

The outer end or bearing 19 of the body 20 integrally carries vertically disposed arm 24 which in turn supports a work-supporting plate 23. The front face of the plate 23 is accurately machined to a smooth finish and is so carried by arm 24 as to lie in a plane perpendicular to the axis of rod 15 and parallel to the plane of the mounting surface 11 on machine 10. In other words, the face of plate 23 is disposed at right angles to the axes of the hone 12 and rod 15 and parallel to the plane of surface 11. The work-supporting member 17 and its plate are so slidably and rotatably positioned on the rod that the face of the plate 23 retains the relation stated in any selected position of the supporting member 17. A work-supporting pin, such as a fillister-head screw 25, is secured to the front of the plate 23 for the purpose of supporting a connecting rod 28 as will be explained hereinafter.

A rod 26 is secured to the bearing 19 diametrically opposite the arm 24 by screw threads or other suitable fastening means. The free end of the rod 26 supports a counter-balance weight 27 secured thereto by set screw 27a a sufficient distance from the axis of the rod 15 to maintain or return the member 17 and its plate 23 to a position approximately 90° above the horizontal axial plane of the rod 15 when no work is supported on the said plate. It follows that if the member 17 and the plate 23 are rotated either clockwise or counterclockwise to an acute angular position and then released, the plate 23 automatically will return to its uppermost or starting position.

In operation, assuming that a new piston pin bearing has been inserted in the bearing holding portion of the connecting rod 28, the workman is required to hone to size and surface finish the bearing to fit a selected piston pin. According to my invention, as an incident to the sizing and finishing operation, the piston pin bearing will simultaneously be aligned with the crankshaft bearing. Inasmuch as the bearing surface of the crankshaft bearing is always disposed at an exact angle of 90° with respect to the end of the said bearing, an end of such bearing is used to locate or position the connecting rod in my fixture. For purpose of illustration, the connecting rod 28 is shown in broken lines in Figure 1. It will be noted that the supporting pin 25, which is disposed at right angle to the face of plate 23, projects into the crankshaft bearing to support a portion of the weight of the connecting rod and at the same time to locate the end of such bearing on the plate 23. The operator holds the end of the crankshaft bearing against the surface of plate with his left hand and rotates the plate 23 and its supporting structure 17 on the rod 15 until the opening in the piston pin bearing aligns with the hone 12. With this arrangement my fixture will accommodate connecting rods having variable center distances between their two bearings, and connecting rods with varying bearing spacings are handled equally satisfactorily simply by moving the plate 23 clockwise or counterclockwise until the piston pin bearing aligns with the hone 12.

The foregoing manipulation is followed by the operator moving the connecting rod 28 rearwardly so that the piston pin bearing receives the hone 12, whereupon the hone 12 is properly adjusted to the bearing and the honing machine 10

operated to rotate the hone. The connecting rod 28 is then moved forwardly and rearwardly upon the hone with the operator holding the connecting rod as above explained. As this is done, the piston pin bearing reciprocates axially on the hone 12 in parallel relationship with the axis of the crankshaft bearing because of the guiding and aligning action provided by the work-supporting plate 23 sliding longitudinally on the rod 15. With the connecting rod limited to the above parallel motion during the reciprocating honing operation, bell-mouthing of the bearing is eliminated.

If, for any reason, the piston pin bearing is not in proper alignment with the crankshaft bearing at the start of the operation, the hone will automatically remove sufficient stock from the proper walls of the piston pin bearing until such walls are brought into parallel relationship with each other and with the walls of the crankshaft bearing. When the operator is satisfied that the bearing has been honed to the proper size no further operations are required. The bearings are in perfect alignment without the necessity of twisting or bending the rod and performing repeated testing operations on expensive test fixtures or gauges. In actual practice, the use of my fixture has reduced the time previously required for honing and aligning the piston pin bearing between 40% and 45% as well as eliminating the necessity of employing highly skilled workmen to perform these operations. When the connecting rod is removed from the work-supporting plate, the plate automatically rotates to its uppermost position because of the counterbalance weight 27 and it is in position to receive the next connecting rod.

My fixture may be used by the ordinary mechanic and excellent results are obtained without a high degree of skill. Its simple and sturdy construction as well as its adaptability to the ordinary bench type honing machine provides an inexpensive fixture capable of producing results that were heretofore unobtainable except with elaborate and expensive machines designed for production work and not found in the ordinary service establishment because of their prohibitive cost. It is understood that the construction shown is for the purpose of illustration only and that variations may be made in it without departing from the scope of the invention as defined by the appended claims.

I claim:

1. In a honing machine having a rotatable hone, a connecting rod aligning and supporting fixture for a connecting rod having a crankshaft bearing and a piston pin bearing, said fixture comprising a fixed supporting shaft adapted to be mounted on the honing machine with its axis parallel with the axis of the hone, a connecting rod supporting member having a part mounted on said shaft for simultaneous axial slide and rotational movements, an alignment plate mounted on said part and having a face disposed at right angles to the axes of said shaft and the hone and adapted to receive and support one end of the crankshaft bearing of the connecting rod, said plate being rotatable through said part toward and from the hone to accommodate connecting rods of varying length with the piston pin bearing thereof receiving the hone, and means for suspending the crankshaft bearing portion of the connecting rod on said plate.
2. In combination with a honing machine having a hone supporting spindle, a movable member

having a vertically disposed plane surface adapted to support the material to be honed, the movable member being radially removed from the hone supporting spindle, a removable support means secured to the honing machine for supporting the movable member with the said vertically disposed plane surface lying in a plane disposed at an angle of 90° with the axis of the hone supporting spindle, the movable member being movable on the removable support means both axially and rotatably simultaneously relative to the hone supporting spindle.

3. In combination with a honing machine having a hone supporting spindle, a removable support means comprising a bar having one end secured to the honing machine, and a rod supported by said bar adjacent its other end in parallel relationship with the hone supporting spindle, a member movable circumferentially and axially on the said rod and having a vertically disposed plane surface lying in a plane disposed at an angle of 90° with the axis of the hone supporting spindle, said plane surface being movable axially and rotatably simultaneously relative to the hone supporting spindle, and support means projecting from said plane surface for supporting the material to be honed, whereby the material to be honed may be positioned and supported on the plane surface and may be reciprocated in parallel relationship with the hone supporting spindle.

4. In a machine having a rotatable tool for sizing bores, a fixture adapted to support and align a work piece having spaced and bored bearing elements disposed with their axes in parallel alignment, said fixture comprising a supporting shaft disposed laterally of the rotatable tool with

its axis parallel with the axis of the rotatable tool, a work piece supporting member having a portion mounted on said shaft for simultaneous axial shift and rotary movement therealong, and an alignment plate mounted on said portion and having a face disposed at right angles to the axes of said shaft and the rotatable tool and adapted to receive and support one end of one of the bearing elements of the work piece with another bearing element of the work piece engaged with the rotatable tool.

5. A fixture adapted to support and align a work piece and comprising a bar, a rod, said rod being circular in cross-section and secured to and adjacent one end of the bar, a member having spaced bearing elements slidably and rotatably mounting said member on said rod, said member having an alignment plate for aligning the work piece and for movement of the work piece with said member on said rod, and means on said plate for supporting the work piece radially removed from said rod.
